UNITED STATES PATENT OFFICE.

CHARLES H. MULLEN, OF SAN FRANCISCO, CALIFORNIA.

BED-LOUNGE.

SPECIFICATION forming part of Letters Patent No. 627,757, dated June 27, 1899.

Application filed October 28, 1898. Serial No. 694,778. (No model.)

To all whom it may concern:

Be it known that I, CHARLES H. MULLEN, a citizen of the United States, residing in the city and county of San Francisco, State of

5 California, have invented an Improvement in Bed-Lounges; and I hereby declare the following to be a full, clear, and exact description of the same.

My invention relates to certain improvements in that class of furniture known as "bed-lounges;" and it consists in details of construction, which will be more fully explained by reference to the accompanying drawings, in which—

15 Figure 1 is a lateral section through the bed-lounge, showing it opened out. Fig. 2 is a similar section showing the back in its usual upright position. Fig. 3 is a perspective view of the head portion of the lounge.

20 The object of my invention is to provide certain improvements in the hinged legs by which the back portion of the lounge is supported when it is let down into a horizontal position, means for tilting and opening the 25 whole device about the containing box or base which contains bedclothing and to which the rear edge of the lounge or sofa portion is hinged, and in other ways to make the device more efficient than at present.

30 A is a box which forms the base upon which the body of the lounge B is supported when in its ordinary position and which forms a cover or closure for the box. This box is intended to contain bedclothing or other articles, and in order to have convenient access to it I have shown strap-hinges C with one leaf of each fixed to the end of the box and the other leaf extending along and fixed to the end of the lounge portion B, the two being pivoted together, so as to turn about the bolt or rivet c, thus allowing the lounge portion to be tilted backwardly, so as to expose the entire interior of the box A.

In order to limit the distance to which the 45 part B can be opened or tilted backwardly, I employ the hinged metallic straps D, pivoted together at their meeting ends, and the uppermost one has its upper end pivoted to an angular strip of metal D', which is bolted beneath the bottom of the part B, as shown. This hinge-strap serves as a check when extended to its full length to prevent the part B

from tipping back too far, and when the part B is closed upon the part A the two straps D D fold within the end of the box and are 55 out of the way.

The part B, which when upholstered forms the seat of the lounge, has connected with it a back, which is capable of being let down into a horizontal position in the same plane with 60 the seat portion B, and when in this position it forms a bed, having a width equal to that of the seat and the back. This back portion E is connected with the lounge portion B by means of iron straps F, which are strongly 65 riveted to the ends B and E, respectively, and are jointed together, as shown at f, thus forming the hinge or fulcrum about which the part E is turnable, so that it may be set into an upright position to form the back for the 70 lounge or let down into a horizontal position, as previously described.

In this class of lounges it is customary and necessary to support the part E upon legs, which are constructed to fold up in line with 75 the part E when the latter stands upright and to be automatically extended when the part E is let down, so as to be in position to support it. These legs are variously hinged and connected with the part E. My object 80 is to make a cheaper, stronger, and more efficient connection in this particular, and in carrying it out I have shown the leg G formed of a strap of iron or steel, the upper part of which stands edgewise in the plane of movement of the back E when it is opened or closed. The upper end of this portion is perforated and is pivoted to a strip of metal H, which is bent so that the two ends project in opposite directions at right angles from the 90 central portion, forming a sort of rectangular Z. One of these arms H' is riveted or bolted to the end frame of the part E. The bend throws the other arm H² inwardly from the end frame E, and to this, as before stated, 95 the upper part of G is pivoted. The central part of the plate G is twisted so that it stands at right angles with the part G, as shown at G'. This part G' is riveted or attached to a bar I, which extends from end to end of the 100 frame E, connecting at the opposite end with a similar leg-bar G' at that end, and it thus binds the two together, so as to increase their rigidity. The lower part of this bar is again

twisted so that it stands in the same plane with the upper part G, as shown at G², and at the bottom it is bent sharply at right angles, forming a table G³, to which the caster-
5 wheel J is attached. The flattened portion G², standing in the same plane with the upper part G and in the plane of movement of the back E, is now in position for the attachment of the brace-bar K, one end of which is
10 pivoted to the part G², as shown at k, and the other end is pivoted to the stationary rearwardly-projecting part B' of the seat B, as shown at k'. By this construction the movement of the back E when opened out
15 about its hinge-points f acts through the curved brace-bar K to extend the leg G' G², so that when the back has reached its horizontal position the casters J will rest upon the floor, and thus support it in a horizontal position. When the back is raised into its approximately vertical position, the bed thus being converted into a lounge, the reverse action straightens the bars G and K approximately into line with each other, the
20 end of the bar K which is pivoted to G² being bent into an angle or arc edgewise, so as to allow of this position of the parts without interfering with the side bar of the part E.

This construction of the parts greatly reduces the cost, as I avoid the use of regular hinges, and I also greatly strengthen the device by being enabled to make it all of iron, the twisting of the bar G' G² enabling me to use the single strip and make the necessary
35 connections without supplemental pieces.

Having thus described my invention, what I claim as new, and desire to secure by Letters Patent, is—

1. The combination in a bed-lounge of the
40 seat portion, a back with straps by which it is hinged at opposite ends of the seat portion so as to be raised or let down into a horizontal position, supporting-legs therefor consisting of a metal plate bent so that the ends
45 stand edgewise in the plane of movement of

the back while the central portion is turned at right angles thereto, a connecting-bar by which said central portions of the legs at opposite ends are connected, a bent Z-shaped piece having one arm secured to the end of
50 the back and to the opposite arm of which the upper end of the twisted leg is pivoted, and a brace connecting the rear of the seat with the lower part of the twisted leg substantially as described. 55

2. In a bed-lounge, the seat and back hinged together as shown, Z-shaped lugs having one arm fixed to the outer ends of the back, and the other forming fulcrums for the legs, a curved brace having one end pivoted to the rear extension of the seat portion of the lounge, and a leg bent so that the ends are in the plane of movement of the back and the center at right angles thereto, said leg having its upper end pivoted to one arm of the Z-
65 shaped lug and having the lower end connected with the pivoted brace-bar, a tablet formed by bending the extreme lower end of said leg at right angles and a caster-wheel the frame of which is riveted thereto. 70

3. In a bed-lounge, a seat and back flexibly hinged together, automatically-foldable legs having opposite ends in the plane of the movement of the back and intermediate portions turned at right angles to said ends, and
75 means connecting said intermediate portions, said legs connected with the seat and the back and extensible to support the back in its horizontal position, a containing-box forming a base and support for said superstructure, hinges connecting the rear of the seat with the coincident edge of the box and hinged connecting-links by which the movement is limited. 80

In witness whereof I have hereunto set my hand. 85

CHARLES H. MULLEN.
